UNITED STATES PATENT OFFICE.

WILLIAM WILLIAMS, OF MURRUMBEENA, VICTORIA, AUSTRALIA.

CARPENTER'S HAMMER.

Application filed November 28, 1923. Serial No. 677,368.

To all whom it may concern:

Be it known that I, WILLIAM WILLIAMS, a subject of the King of Great Britain, and a resident of Railway Park, Murrumbeena, 5 in the State of Victoria, Australia, have invented new and useful Improvements in Carpenters' Hammers, of which the following is a specification.

This invention relates to improvements in 10 carpenters' hammers and refers especially to hammers having a claw for pulling nails out of wood or the like.

It is customary to provide claw hammers with a deep eye for the handle and to form 15 a round face on one side and a curved nail pulling claw on the other side of the eye. It has been proposed to provide the eye of the hammer with an auxiliary claw or claws arranged more or less parallel with and converging in the same direction as the nail 20 pulling claw.

The object of the present invention is to provide exceedingly simple and efficient means whereby a powerful leverage can be 25 obtained on a long nail without any liability of the nail becoming disengaged from or slipping out of engagement with the hammer, even when it has been partially extracted or when the head is at a distance 30 from the driven portion.

I accomplish the above-mentioned object by providing the hammer near the top of the eye with jaws for engaging the head or shank of a nail and having the sides thereof 35 of converging in an opposite direction to the claw, whereby when a nail is partially withdrawn by the claw, the said head can be inserted and held in the said engaging jaws, so that the fulcrum point is altered 40 and allows the nail to be extracted without necessitating the tilting of the hammer to such an extent as to occasion material loss of leverage.

In order that the invention may be 45 readily understood, reference will now be had to the accompanying sheet of explanatory drawings wherein

Figure 1 is a view in perspective of a hammer constructed in accordance with the present invention. In this view the hammer is shown in position drawing a long nail from a piece of wood.

Figure 2 is a view in sectional elevation

taken on the plane 2—2 of Figure 1 and shows portion of the claw and head of the 55 hammer.

Figure 3 is a view in sectional side elevation taken on the dotted line 3—3 of Figure 2 and shows a modification of the invention which will be hereinafter fully described.

Figures 4, 5, 6, 7 and 8 are views in perspective of part of a hammer showing further modifications of the invention.

Figure 9 is a view in sectional side elevation of part of the hammer.

Figure 10 is a view in sectional elevation taken on the plane 10—10 of Figure 8.

In these drawings like characters of reference indicate the same or corresponding parts 70 in the different views and the letter *a* designates the eye of a carpenter's hammer having a face *b* on one side and a rearwardly diverging claw *c* on the other side thereof of ordinary design.

The top of the eye is provided with means for engaging the head or portion of a nail *c* adjacent to the head whereby when a long nail is partially drawn the hammer can be tilted so that the head or shank of the partially drawn nail is gripped by the said engaging means whereby a second pull can be had on the nail and the outer face of the claw acts as a fulcrum.

The means on the top of the eye of the 85 hammer for engaging the head or shank of the nail may vary in construction and in the drawings several different forms of engaging means have been illustrated.

In Figures 1, 2, and 3 the engaging means 90 on the upper part of the eye comprise a pair of rearwardly converging jaws *d* formed longitudinally on the eye at the rear of a hole *e* in the said eye.

When a nail is pulled halfway or for a portion of its length from a piece of wood *f* the head will be disposed as shown in dotted lines at *g* in Figure 1 and when the shank is disengaged from the claw *c* and the head inserted in the hole *e* it may be passed between the jaws *d* in which position the ends of the claw are bearing against the wood *f* and when the handle *h* of the hammer is pulled outwardly in the ordinary way to draw a nail, a powerful leverage will be obtained which in most cases will be sufficient

to pull nails of a considerable length and without materially bending that portion which lies between the claw of the hammer and the face of the piece of wood from 5 which the nail is being drawn.

In Figures 1, 2, and 3 of the drawings the jaws *d* are formed by pressing up portions of the top part of the eye of the hammer and the sides of the jaws converge as they 10 pass away from the hole *e*. The converging sides of the jaws enable nails of different thickness or gauge to be gripped and retained in position when the second pull is obtained on the nail.

15 The hole *e* may extend right through the eye and handle of the hammer as shown in Figure 3 of the drawings so that when an extra long nail is to be drawn it may be drawn in three stages, first by means of the 20 claw *c*, secondly by means of the claw *c* and the jaw *d*, and the third operation by passing the head of the nail through the hole *e* and again pulling on the handle and using the outer face of the claw as a ful- 25 crum.

In the modification shown in Figure 4 of the drawings the jaw *d* is formed on top of the eye and is of sufficient dimensions to engage different sizes of nails.

30 In Figure 5 of the drawings the jaws *d* are shown riveted to the top of the eye of the hammer and in Figure 6 of the drawings, the jaws are formed with downwardly projecting lugs *i* which are secured to the 35 sides of the eye by means of rivets or screws *j*. If preferred the jaws *d* shown in Figure 5 can be formed integrally with the eye.

The jaws shown in Figures 1 to 6 have 40 their converging sides undercut to provide clearance for the head of a nail to be moved rearwardly therebetween to enable it to be retained firmly between the jaws when the nail is being drawn by the claw and jaws.

45 Moreover the jaws shown in the above-mentioned figures are opened at both ends but it will be obvious that the rear or narrower end may be made closed.

In Figure 7 of the drawings the top of 50 the eye is formed with a converging slot *k* which terminates in a hole *e* formed in the said eye. The wooden handle immediately below the sides of the converging slot *k* is cut away to form a jaw which is adapted to 55 engage the shank of the head near the nail when a second pull is desired to be had on the nail.

In Figure 8 of the drawings the top part 60 of the eye is shown extending along the handle of the hammer as at *l* to accommodate an auxiliary engaging means *k'* for the nail and constructed somewhat as shown in Figure 7 of the drawings.

When two auxiliary slots or pair of en- 65 gaging members *k'* are provided on the eye

they can be made uniform in size or one can be made larger than the other.

Figure 9 is a view in longitudinal section of part of Figure 8 and clearly shows the cut away portion of the handle beneath the 70 edges of the said slots.

Figure 10 which is a cross sectional view of the eye of the hammer on the plane 10—10 of Figure 8 also shows portion of the handle cut away to provide clearance for the 75 head of a nail.

In an alternative construction the top part of the eye can be formed with an upwardly extending flange *m* which forms a socket and is adapted to surround the converging sides 80 of the jaws *d* or slots *k'* whereby the second grip may be obtained on the head of the nail. The upward projecting flange *m* is shown in Figures 6, 8, and 9 and the said flange *m* can be used independently of or in con- 85 junction with the jaws *d* or the slot *k*.

When the head of a driven nail is at some distance from the piece of wood from which it is to be extracted, the head thereof is engaged by the auxiliary engaging means on 90 the eye, and the hammer is tilted by pulling on the handle thereof. The curved face of the outer claw rolls over the surface of the piece of wood and acts as a fulcrum to enable a powerful leverage to be obtained 95 and the nail to be easily extracted.

When the nail is driven nearly home, the outer claw can be used to partially extract it and then the auxiliary claw or engaging means can be used to hold the head of the 100 nail while the operation is being completed.

The invention is simple in construction and in use will be found thoroughly efficient for the purpose for which it has been devised.

105 I claim:—

1. A carpenter's hammer having an eye for receiving a handle and provided with a face on one side and a rearwardly diverging claw on the opposite side thereof, rearwardly 110 converging jaws on the side of the eye provided with the claw, said jaws being adapted to receive the head of a partially drawn nail and hold the shank while the hammer is operated to completely draw the nail. 115

2. A carpenter's hammer having an eye for receiving a handle and provided with a face on one side and a rearwardly diverging claw on the opposite side thereof, rearwardly converging jaws on the side of the eye provided with the claw, and a hole in the eye between the converging end of the claw and the diverging ends of the jaws, substantially as described. 120

3. A carpenter's hammer having an eye for receiving a handle and provided with a face on one side and a rearwardly diverging claw on the opposite side thereof, rearwardly converging jaws on the side of the eye provided with the claw, a hole in the 125 eye

eye between the converging end of the claw and the diverging ends of the jaws, and a flange formed on the eye and adapted to surround the hole therein, substantially as described.

4. A carpenter's hammer having an eye for receiving a handle and provided with a face on one side and a rearwardly diverging claw on the opposite side thereof, rear-

wardly converging jaws on the side of the eye provided with the claw, the opposing faces of the said jaws being shaped to firmly grip the shank of a partially drawn nail, substantially as described.

In testimony that he claims the foregoing as his invention, he has signed his name.

WILLIAM WILLIAMS.
